UNITED STATES PATENT OFFICE

170,540

CREAM SEPARATOR

Lawrie G. McIntosh, Toronto, Ontario, Canada,
assignor to Massey-Harris Co. Ltd., Toronto,
Ontario, Canada, a corporation of Canada

Application April 14, 1953, Serial No. 24,488

Term of patent 14 years

(Cl. D23—1)

To all whom it may concern:

Be it known that I, Lawrie G. McIntosh, a citizen of Canada, residing in Toronto, in the county of York and Province of Ontario, have invented a new, original, and ornamental Design for a Cream Separator, of which the following is a specification, reference being had to accompanying drawing forming part thereof:

Figure 1 is a perspective view from the right side of the cream separator, showing my new design.

I claim:

The ornamental design for a cream separator, substantially as shown.

LAWRIE G. McINTOSH.
